UNITED STATES PATENT OFFICE.

HENRY J. KIRKPATRICK, OF TORONTO, ONTARIO, CANADA, ASSIGNOR TO THE BOECKH COMPANY, LIMITED, OF TORONTO, CANADA.

SHAVING BRUSH.

Application filed June 16, 1923. Serial No. 645,753.

This invention relates to shaving brushes and my object is to provide a brush that is sanitary, that can be readily sterilized without damaging it and is well balanced and no heavier than the average good brush.

I attain my object by means of the constructions hereinafter described and illustrated in the accompanying drawings in which—

10 Fig. 1 is a longitudinal section of my improved brush; and

Fig. 2 a cross section on the line 2—2 in Fig. 1.

The brush knot 1 is dipped in a rubber solution and then set in a ring 2. The purpose of the ring is to act as a binder to prevent the knot spreading while being set. The metallic handle 3 is hollow and is formed with a segmento-spheroidal portion 4 adjacent one end, the ring 2 being adapted to be seated within this portion 4 to prevent the withdrawal of the ring through one end of the handle. The preferred method of accomplishing this is to provide a seat 5 at the end of the handle, which seat is formed by turning in the lower edge of the segmento-spheroidal portion. Adjacent the upper end of the portion 4 the handle is provided with a bead 6 and from this bead 30 the handle flares outwardly to form a bell mouthed end 7.

The mode of assembling the brush is as follows. The knot of the brush hair or bristles with its ring 2 is passed through the bell mouthed end 7 of the handle and the ring engaged with the seat 5. It is obvious that the knot may be arranged to directly engage the seat 5 instead of indirectly engaging it. The handle is then held in a vertical position and sealing means, preferably molten lead 8 or other readily fusible

metal, is filled in or poured over the ring and the brush knot. The handle is preferably formed from spun aluminum and the sealing means, applied in a plastic or liquid state, has a tendency to adhere thereto, but is preferably of such a depth that it extends up sufficiently far to be held down against the brush knot and ring 2 by the incurve of the sides of the segmento-spheroidal portion 4. Above the sealing plug 8 the handle is filled with a suitable filling material such as powdered cork 9 and the end 7 is sealed as hereinafter described.

The bell mouthed end 7 is shaped to form 55 a definite shoulder 10 against which a disk 11 may be seated. This end is closed by a cap 12 having a rim which is inwardly rolled against the outer surface of the handle adjacent the open end, the purpose 60 of the disk being to provide a form on which the cap rim and the end of the handle are inwardly rolled to prevent the hollow handle being crushed in during this inrolling operation. By this method a substantially water tight hollow handle is provided, and if any water does get in, the amount would be very small owing to the space 65 being substantially filled with powdered cork.

70 What I claim as my invention is:—

A shaving brush comprising a hollow metal handle; a brush knot adapted to be seated and sealed in one end of the handle; and a cap adapted to seal the other end of 75 the handle, the handle being filled with powdered cork to exclude moisture therefrom.

Signed at Toronto, Canada, this 8th day of June, 1923.

HENRY J. KIRKPATRICK.
